Perreault & Pfleger, PLLC

(57) **CLAIM**

We claim the ornamental design for a vacuum cleaner, as
shown and described.

DESCRIPTION

FIG. 1 is a front view of a vacuum cleaner showing our new
design;

FIG. 2 is a rear view thereof;

FIG. 3 is a top view thereof;

FIG. 4 is a bottom view thereof;

FIG. 5 is a left view thereof;

FIG. 6 is a right view thereof;

FIG. 7 is a perspective front, top, right view thereof;

FIG. 8 is perspective front, bottom, right view thereof;

FIG. 9 is perspective rear, top, left view thereof;

FIG. 10 is perspective rear, bottom, left view thereof;

FIG. 11 is perspective front, top, left view thereof;

FIG. 12 is perspective front, bottom, left view thereof;

FIG. 13 is perspective rear, top, right view thereof; and,

FIG. 14 is perspective rear, bottom, right view thereof.

The broken lines in the drawings depict portions of the
vacuum cleaner that form no part of the claimed design.

1 Claim, 11 Drawing Sheets
